UNITED STATES PATENT OFFICE.

ABRAHAM PACHNER, OF NEW YORK, N. Y., ASSIGNOR OF TWO-THIRDS TO
SALI SIMONSON AND ISAAC PACHNER, OF SAME PLACE.

CAP OR HEADWEAR.

SPECIFICATION forming part of Letters Patent No. 677,321, dated June 25, 1901.

Application filed March 15, 1901. Serial No. 51,285. (No model.)

To all whom it may concern:

Be it known that I, ABRAHAM PACHNER, a citizen of the United States, residing at Manhattan borough, in the city, county, and State 5 of New York, have invented new and useful Improvements in Caps or Headwear, of which the following is a specification.

This invention relates to a cap or headwear having a so-called "forehead-protector;" and 10 the invention resides in the novel features of construction set forth in the following specification and claim and illustrated in the annexed drawings, in which—

Figure 1 shows the protector out of action. 15 Fig. 2 shows the protector in action or protecting position. Fig. 3 shows an inner or under view of the cap.

The cap or headgear 1 is shown with a vizor or brim. This vizor has the upper part 2 made 20 stationary or fixed to the body or crown of the cap or article, and said vizor or upper section or layer 2 is provided with a movable under vizor or layer 3. This latter can be lowered to form a forehead-protector or raised to be 25 out of the way, as when the cap is to be worn in the ordinary manner or in moderate weather. This under part 3 of the vizor being movable or made to drop and rise can be moved to and from protecting position without affecting 30 the fixed vizor part. A sweat-band is shown at 4, which when made to extend to or engage the upper vizor-section 2 only will leave the inner edge of the protector part 3 movable to be lowered or raised, as required, 35 so as to come to and from protecting position. The protector 3, moving on the vizor, can be set to and from protecting position, and the fit of the article will not be affected, while if a protector is made to fold into and out of the 40 cap proper the size or fit might be varied.

In the example shown the protector part of the vizor is provided with stiffening or spring pieces of suitable material—as, for example, pasteboard, buckram, or other substance. 45 These spring-pieces 5 being sewed or stitched in place along suitable lines 6 will give a certain rigidity or spring to the protector. These two pieces, hinging or swinging with respect to one another, allow the protector to bend

so that the front or outer part of the protector can sit up to the vizor, while the inner protector portion can come down to the eyebrows or cover the forehead of the wearer. The stiffening, however, has not been found absolutely necessary, but is practical for holding the protector part of the vizor in shape as well when in as when out of protecting position. It has also been found that in place of two spring-pieces 5 only one will answer, and in the latter case the outermost stitch or 60 stitches 6 could be omitted.

When the protector is lowered or in action, it has been found that the space or air between this protector 3 and vizor 2 lying at an angle to one another keeps the heat or 65 warmth confined to the forehead, thus securing efficient protection against cold.

The protector, as also the vizor, can have the faces lying toward one another lined, if seen fit. This construction has been found 70 economical, as it saves the material or strip heretofore required for forehead-protectors and which called for a separate band.

The movable under part or protector 3 is sewed to the upper vizor 2 and the inner edge 75 of such under vizor 3 is left free to form the movable protector. This protector is applicable to various styles of cap or headwear having a vizor. The movable under vizor could be made movable all the way to the 80 outer edge or only part way out—say to one of the seams 6.

What I claim as new, and desire to secure by Letters Patent, is—

1. A head-covering having a vizor and a 85 protector permanently connected to the vizor along the lower inner edge thereof, the upper portion of the protector being free and being arranged to normally lie flatwise against the inner side of the vizor, and springy stiffening material between the plies of the protector.

2. A head-covering having a vizor and a protector connected with the vizor along the lower edge of the vizor, said protector being 95 free of the vizor above said edge and being integral with said vizor and arranged to normally lie flatwise against the inner face thereof.

3. A head-covering having a vizor and a
protector connected with the vizor along the
lower inner edge thereof, the upper portion
of the protector being free and being arranged
5 to normally lie flatwise against the inner side
of the vizor.

In testimony whereof I have hereunto set

my hand in the presence of two subscribing
witnesses.

ABRAHAM PACHNER.
